UNITED STATES PATENT OFFICE.

PARKER DUNNING, OF SCHENECTADY, NEW YORK, ASSIGNOR TO GENERAL ELECTRIC COMPANY, A CORPORATION OF NEW YORK.

LOCK FOR SWITCHES OR THE LIKE.

1,290,938.

Specification of Letters Patent.

Patented Jan. 14, 1919.

Application filed January 5, 1917. Serial No. 140,825.

To all whom it may concern:

Be it known that I, PARKER DUNNING, a citizen of the United States, residing at Schenectady, in the county of Schenectady, State of New York, have invented certain new and useful Improvements in Locks for Switches or the like, of which the following is a specification.

My invention relates to means for locking switches against operation under certain conditions and provides improved means whereby the switch may be easily and securely locked in a certain position so that it cannot be tampered with.

My invention relates more specifically to means for locking a switch handle in a definite position as, for instance, in an inoperative position, and is particularly applicable to a switch having an operating handle which is attached to and rotates a switch actuating shaft and which is ordinarily removable from the shaft. In the case of a switch such, for instance, as a transformer switch for starting alternating current motors which is commonly known as a "starting compensator", the operating handle is removably secured to the actuating shaft and normally assumes an inoperative position. The handle is removably secured to the shaft for convenience in assembling the compensator and for disassembling in order to make repairs. It is frequently necessary to prevent the operation of this switch by unauthorized persons and my invention as applied to a switch of this character prevents the operation of the switch mechanism either by means of the switch handle or by removing the handle and operating the switch shaft by other means as, for instance, a wrench.

In carrying out my invention I provide means whereby the switch handle is not only locked in its inoperative position but it is also locked to the shaft. I accomplish this by a very simple arrangement involving the use of only a single lock and key. My arrangement also has the advantage that under all conditions the lock is not removed from its place and there is, therefore, no necessity for carrying it around and no danger of its being lost.

In carrying my invention into effect, in one form I provide a removable pin which is reversible so that in one position it oper-

ates to prevent the movement of the switch handle and in the other position permits the movement of the handle, but in both positions the pin is locked in place and the handle is locked to the shaft.

I have shown my invention applied to a transformer starting switch or compensator of the type shown and described in my previous Patent No. 970,478, dated September 20, 1910, to which reference may be made to the details of the switch mechanism. It is obvious, however, that my invention is applicable to other types of devices.

Referring to the drawings showing an embodiment of my invention in a starting compensator for alternating current motors, Figure 1 is a front elevation of the compensator showing the switch handle locked in the neutral or "off" position, and Fig. 2 is a detail side view of the switch handle and a part of the compensator with certain parts broken away and shown in section for the sake of clearness.

Referring to the figures, the starting compensator has a cover 1 which incloses the transformer coils of the compensator and the bottom section 2 incloses the switch contacts which are provided for starting the alternating current motor with a reduced voltage and for connecting the motor directly to the source of supply for full speed running after the motor has come up to the full starting speed. The switch handle 3, when not locked in the neutral position as shown, is adapted to be moved both ways from the neutral position shown in the drawings to circuit closing positions, the arrangement being such that by moving the switch handle 3 to the right the motor will be connected to the source of supply with a reduced voltage and the motor accelerated, after which moving the handle quickly to the left will connect the motor directly to the source of supply with full voltage for full speed running. The handle 3 is removably attached to the shaft 4 to which the movable contact members of the switch are connected by means of the bolt 4' which is screwed into the end of the shaft. The handle is shown as locked in the "off" position by means of a movable member, the removable pin 5, carried by the switch handle, the arrangement being such that one end of this pin is adapted to make locking engage-

ment with a stationary part of the structure, in this case the compensator case, to prevent movement of the switch from the "off" position. A hinged hasp-like securing device 6 is provided for this removable pin 5 and this securing device has an aperture through which the end of the pin which is not in engagement with the compensator case is adapted to pass. This securing device 6 engages a shoulder on the pin 5 to prevent unauthorized removal of the pin when the handle is in the locked position or when the handle is free to be moved to the operative positions, as will be herein-
15 after more fully described. The securing device 6 is preferably in the form of a hasp and is hinged at one end to the switch handle. An aperture in the other end is provided for interlocking with bolt 4', in the
20 end of the shaft 4 to secure the securing device 6 in position on the switch shaft, thereby preventing unauthorized removal of the pin 5 from the switch handle or removal of the switch handle from the switch shaft.
25 The pin 5 has two end portions of reduced diameter, the end portion 8 being longer than the end portion 9. The end portion 8 is sufficiently long to make locking engagement with a hole in the com-
30 pensator case to lock the switch handle in the "off" position. The end portion 9 is of such a length that when the pin is re-
versed in its position in the switch handle from that shown in the drawings, the switch
35 handle can be moved from the "off" position to the circuit closing positions, the end portion 9 operating to make engagement with the stop lugs 10 and 11 and thereby arrest the motion of the switch
40 handle at the proper operative positions. There are abrupt shoulders between the main portion of the pin 5 and the end portions, the arrangement being such that when the pin is inserted in the opening of the
45 switch handle, the securing device 6 dropped into position and the lock 7 secured to the switch shaft, the end 8 or 9 of this pin, depending upon the one being used, will project the proper distance from the switch
50 handle and be securely held in this position to perform the functions for which this locking arrangement is provided.

The operation of my invention is as follows:

55 As before stated, the switch handle 3 is shown in the drawings as being locked in the "off" position. To unlock this handle and thereby render it possible to move the switch to the circuit closing positions, the
60 lock 7 is unlocked and withdrawn from the bolt 4' in the end of switch shaft 4. The securing device 6 may now be lifted out of locking engagement with shaft and the bolt 4' and raised so that the pin 5 may be with-
65 drawn and reversed in position in the switch

handle so that the end 9 will be operative to arrest the handle at the circuit closing positions. The securing device 6 is then dropped into place and the aperture in the end of this device makes locking engagement with the bolt 4' and the shaft as shown in the drawings. The lock 7 is then applied to the switch shaft and the pin 5 cannot be withdrawn from its position in the switch handle except by an authorized person having a key to the lock 7. The switch handle 3 is also locked in its position on the switch since the handle cannot be removed until the lock 7 is withdrawn from the end of the shaft. The pivoted latch 12 is pro-
70 vided for preventing the operator from go-
ing directly to the full running position, the
position to the left, and compels him to
throw the switch arm to the starting posi-
75 tion, the position to the right. When the
operator throws the switch handle to the
right to start the motor the end 9 of
the pin 5 will make engagement with the
stop lug 10 and thereby arrest the further
80 rotation of the switch arm in this direction
and the movable contact members of the
switch (not shown) will make contact with
a set of stationary contacts (not shown) to
connect the motor to the source of supply
85 with a reduced voltage in a well known
manner. After the motor has come up to
full starting speed, it may be connected di-
rectly to the source of supply at full voltage
and thereby accelerate the motor to the full
90 running speed by moving the switch handle
quickly to the left, thereby throwing the
latch 12 upward and rendering it ineffective
to arrest the movement of the switch arm
at the "off" position and permit it to be
95 moved until the end 9 of the pin 5 makes
engagement with the stop lug 11 at the
full voltage normal running position of the
switch.

With the switch arm to the left, the full running position, if it is desired to stop
10 the motor and lock the switch arm in the
"off" position and thereby prevent opera-
tion of the switch except by an authorized
person, the switch arm is thrown to the
"off" position, the lock 7 unlocked and re-
105 moved from the switch shaft 4, the se-
curing device 6 lifted, the pin 5 withdrawn
from the opening in the switch handle and
then reversed, and reinserted in the switch
handle so that the end 8 makes a locking
110 engagement with the compensator case. The
securing device 6 is then dropped into place,
covering the pin 5 and making locking en-
gagement with the bolt 4' in the end of the
switch shaft 4 so that when the lock 7 is
115 applied the securing device cannot be lifted
to remove the pin 5 from its position in
the switch handle and the switch handle
cannot be removed until the lock 7 is with-
drawn. As before stated, the arrangement
120

of the parts when the switch is locked in the "off" position is that shown in the drawings.

While I have described a specific embodiment of my invention, it should be understood that I do not limit by invention thereto since various modifications may be made therein without departing from the spirit of my invention, the scope of which is set forth in the claims which are hereto annexed.

What I claim as new and desire to secure by Letters Patent of the United States, is:—

1. The combination with a switch or the like and a handle for operating the same, of means for locking the handle in a predetermined position comprising a movable member which in one position prevents movement of the handle and in the other position permits such movement, and means including a lock whereby the member is secured in each position and the handle is secured against removal in both positions.

2. The combination with a switch or the like and a handle for operating the same, of means for locking the handle in a predetermined position comprising a movable member carried by the handle which in one position prevents movement of the handle and in the other position permits such movement, a lock and means whereby in each position of the member the lock secures the member in position and also secures the handle against removal.

3. The combination with a switch or the like having a shaft and a movable handle attached thereto for operating the same, of means for locking the handle in a predetermined position and securing the handle against removal from the switch shaft comprising a movable member which in one position prevents movement of the handle and in the other position permits such movement and means including a lock for securing the member in each position and for securing the handle to the switch shaft in both positions.

4. The combination with a switch or the like and a handle for operating the same, of means for locking the handle in a predetermined position comprising a movable member which in one position prevents movement of the handle and in the other position permits such movement, a securing device and a lock for securing the said device in position to prevent unauthorized movement of the said member from either position and to secure the handle against removal in both positions.

5. The combination with a switch or the like and a handle for operating the same, of means for locking the handle in a predetermined position comprising a movable member carried by the handle which in one position prevents movement of the handle and

in the other position permits such movement, a securing device hinged to the handle and a lock for securing the free end of said device in position to prevent unauthorized movement of the said member from either of its positions and for securing the handle against removal in both positions.

6. The combination with a switch or the like having a shaft and a handle attached to the shaft for operating the same, of means for locking the handle in a predetermined position comprising a movable member carried by the handle which in one position prevents movement of the handle and in the other position permits such movement, a securing device for the said member having one end hinged to the handle and an aperture in the free end adapted to interlock with the switch shaft, and a lock for securing the free end of said device in position to prevent unauthorized movement of the said member from either of its positions.

7. The combination with a switch or the like and a movable handle for operating the same, of means for locking the switch in a predetermined position comprising a pin carried by said handle and removable therefrom to reinsert in a reversed position, said pin being movable into locking engagement with a stationary part of the switch structure, a securing device for the pin, and a lock for securing the said device in position to prevent unauthorized removal of the pin in either position.

8. The combination with a switch or the like and a movable handle for operating the same, of means for locking the switch in a predetermined position comprising a removable pin carried by the said handle and adapted to be moved into locking engagement with a stationary part of the switch structure, a securing device for the pin having one end hinged to the handle, and a lock for securing the free end of the said device to the handle to prevent unauthorized removal of the pin from the locking relation.

9. The combination with a switch or the like and a movable handle for operating the same, of means for locking the switch in a predetermined position comprising a removable pin adapted to be inserted through an opening in the switch handle and moved into locking engagement with a stationary part of the switch structure, a securing device for the pin having one end hinged to the handle, and a lock for securing the free end of the said device to the handle to prevent unauthorized removal of the pin from the locking relation.

10. The combination with a switch or the like having a shaft and a movable handle attached thereto for operating the same, of means for locking the switch in a predetermined position comprising a removable pin

carried by the said handle and adapted to be moved into locking engagement with a stationary part of the switch structure, a securing device for the pin having one end secured to the said handle and the other end adapted to engage the switch shaft, and a lock for securing the said device in position on the switch shaft to prevent unauthorized removal of the pin from the locking relation 10 and removal of the handle from the switch shaft.

11. The combination with a switch or the like having a shaft and a removable handle attached thereto for operating the same, of means for locking the switch in a predetermined position comprising a removable pin carried by the said handle and adapted to be moved into locking engagement with a stationary part of the switch structure, a securing device for the pin having one end secured to the said handle and an aperture in the other end adapted to interlock with the switch shaft, and a lock for securing the securing device in position on the switch shaft to prevent unauthorized removal of the pin from the locking relation and removal of the handle from the switch shaft.

12. The combination with a starting compensator for an electric motor having a

switch shaft and a handle secured to the shaft for operating the switch both ways from a neutral position to circuit closing positions, of means for locking the handle in the neutral position or arresting its movement at a circuit closing position as desired, comprising a removable double-ended pin carried by the said handle, one end of the said pin adapted to be moved into locking engagement with a stationary part of the compensator to lock the handle in the neutral position, the other end of said pin adapted to engage a stationary part of the compensator to arrest the movement of said handle at said circuit closing positions, only one of the ends of said pin being operative at a time, a securing device for the pin having one end secured to the said handle and an aperture in the other end adapted to interlock with the switch shaft, and a lock for securing the said device in position on the switch shaft to prevent unauthorized removal of the pin from the switch handle and to prevent removal of the handle from the switch shaft.

In witness whereof, I have hereunto set my hand this 4th day of January 1917.

PARKER DUNNING.
